UNITED STATES PATENT OFFICE.

DOMINICK BARRETT, OF MAYWOOD, ILLINOIS.

CURLING-IRON.

SPECIFICATION forming part of Letters Patent No. 514,430, dated February 6, 1894.

Application filed March 18, 1893. Serial No. 466,696. (No model.)

To all whom it may concern:

Be it known that I, DOMINICK BARRETT, a subject of the Queen of Great Britain, residing at Maywood, in the county of Cook and State 5 of Illinois, have invented certain new and useful Improvements in Self-Heating Curling-Irons, of which the following is a specification.

This invention relates to certain new and 10 useful improvements in curling-irons, and is more especially adapted to that class of such devices, which are employed for curling the hair; and it consists in certain peculiarities of the construction, novel arrangement, and 15 operation of the parts thereof, as will be hereinafter more fully set forth and specifically claimed.

The objects of my invention are first, to provide a curling-iron, which shall be simple 20 and inexpensive in construction, strong and durable, yet effective in operation; and second, such a device which will be self-heating, and the ignited wick of which can be readily extinguished, when not in use.

In order to enable others skilled in the art, 25 to which my invention pertains to make and use the same, I will now proceed to describe it, referring to the accompanying drawings, in which—

Figure 1, is a perspective view of my invention. Fig. 2, is a longitudinal sectional view thereof. Fig. 3, is a longitudinal sectional view of a portion of the curling tube, showing 30 the method of removing the wick therefrom; and Fig. 4, is an enlarged detail end view of the removable end-piece.

Similar letters refer to like parts throughout the different views of the drawings.

A, represents the body or main piece, and 40 is preferably cylindrical in form as shown in the drawings, and is provided with a hollow or bore a, extending longitudinally through its center.

To one end of the piece or body A, is secured 45 in any suitable manner a pneumatic bulb or bellows B, which is preferably constructed of rubber, and is usually provided with a tubular piece E, which piece is screw-threaded and adapted to engage with screw-threads in the 50 bore a, as is clearly shown in Fig. 2, of the drawings. To the opposite end of the main piece A, is secured in any suitable manner a

tube D, which is made of metal or other suitable material, and of proper length and sufficient size to receive a wick F, which may be 55 made of any desirable combustible material, but preferably of a tinder-like substance or porous or fibrous material.

Within the free end of the tube D, is fitted 60 an end-piece C, the inner portion of which is provided with longitudinal corrugations c, in order to admit a draft of air to the wick through the tube.

To the main piece or body A, is pivotally 65 secured or fulcrumed a thumb-lever G, which extends longitudinally and parallel with the tube D, and when in its normal position lies closely thereto, and is provided at its inner end with a thumb-piece g, and near said end, with a spring h, which spring is adapted to 70 retain the said lever in its normal position, as shown in Figs. 1, and 2, but will yield slightly and allow it to be raised from the tube D, when pressed upon with the thumb, at the point g, thus enabling the operator to place 75 a portion of the tress of hair between the tube D, and the lever G, where it will be retained when the thumb is removed from the thumb-piece by reason of the action of the spring.

In order to prevent the heat being imparted 80 to the hand from the main piece or body A, I may provide the same with a covering a', of felt or some suitable non-heat-conducting material.

The end-piece C, may be used for ejecting 85 the wick F, as is shown in Fig. 3, in which operation the tube D, is removed from the main-piece A, when the end-piece C, may be placed within its hollow and will serve to push the wick therefrom, as is clearly illustrated 90 in said figure.

The operation of my device is simple and as follows: When it is desired to use the iron, the piece C, is removed from the free end of the tube D, and a match or taper is lighted and 95 held to said end, when by pressing upon the bulb and then releasing the same, a draft of air will be drawn thereby through the tube D, which will cause the wick to become ignited from the burning match or taper, and by repeating the operation of squeezing and releasing the bulb, will be caused to burn either rapidly or slowly as desired, and to impart heat to the tube D, which is made of thin

sheet metal, in order that it will easily heat. The consumption of the wick may also be regulated by replacing the piece C, within the free end of the tube D, when the corrugations 5 c, will admit a smaller amount of air. When it is desired to extinguish the wick, the piece C, may be removed and the thumb or finger placed over the free end of the tube D, which action will exclude air therefrom, and of course will extinguish the fire or flame.

Instead of constructing the tube D, and piece A, of separate pieces as above described, I may sometimes, use one piece only, in which construction the lever G, and bulb B, may be 15 attached thereto as before described or in any suitable way.

Having thus fully described my invention, what I claim as new, and desire to secure by Letters Patent, is—

As an improved article of manufacture, a 20 curling iron consisting of a tube, a wick adapted to fit in the same, a pneumatic bulb attached to one end of said tube, and a spring-actuated-lever connected thereto, and a movable end-piece having corrugations, adapted 25 to fit in the free end of the tube, substantially as described.

DOMINICK BARRETT.
